UNITED STATES PATENT OFFICE.

ANDREW L. KULICK, OF DETROIT, MICHIGAN.

SPARK-PLUG.

1,321,217.

Specification of Letters Patent.

Patented Nov. 11, 1919.

Application filed October 24, 1918. Serial No. 259,465.

To all whom it may concern:

Be it known that I, ANDREW L. KULICK, a citizen of the United States, residing at Detroit, county of Wayne, State of Michigan, have invented a certain new and useful Improvement in Spark-Plugs, and declare the following to be a full, clear, and exact description of the same, such as will enable others skilled in the art to which it pertains to make and use the same, reference being had to the accompanying drawings, which form a part of this specification.

My invention relates to spark plugs and consists in making a double ended spark plug which can be readily adapted to be reversed so that the upper or outer end can be substituted as a sparking device for igniting mixture in engines in the ordinary way.

20 In the drawings:

Figure 1 represents a vertical view of the spark plug as assembled and located for use.

Fig. 2 is a vertical section of the spark plug as assembled.

Fig. 3 is a vertical view of the porcelain and core wire.

Fig. 4 is a cross section on the line X—X of Fig. 2.

30 Fig. 5 shows an alternative means for attaching the line terminal to the core wire.

Fig. 6 shows an alternative construction of the terminal connections to the core wire.

Similar letters refer to similar parts.

35 In the drawings A represents the porcelain of the core wire B. The porcelain has the shape shown in Fig. 3, the core wire is formed with a screw thread C at each end, the two ends being exactly alike. B is one-

40 half of the metal casing carrying these parts, E is the other half. The part D is screwed onto the part E as shown at F in Fig. 2. Suitable gaskets G G are interposed between the metal shell and the por-

45 celain insulator for the purpose of making them gas tight. At H I have shown one form of means for attaching the line wire which consists of an insulating sleeve H' slipped over the core wire spreading out

50 from the core wire B and ignition ground J and interposed between it and the core wire B. A screw collar K is run down on the core wire and fastens the sleeve H in place. Between that and the nut L the line

55 wire may be attached in the usual manner. As an alternative construction means for at-

taching the line wire to the core wire I have provided a collar M which is screwed over the pipe thread N on the metal casing carrying with it an insulating piece P over 60 the core wire which has the form shown in the drawing, this projecting over the core wire forces from the core wire the ground terminal J and insulates it therefrom. A thumb nut L' holds the line terminal in 65 place in the usual manner.

In Fig. 6 I have shown an alternative construction which avoids extending the core wire to beyond the sparking point and also avoids cutting a screw thread upon it. In 70 this drawing M is the same cap as is shown in Fig. 5. P' is an insulating sleeve and P² is a portion thereof formed into a collar carried under the cap M and held thereby. Inside of the insulating material 75 is a metal sleeve S which is outside threaded at its upper end and receives the thumb nut L and also the terminal K which the thumb nut secures to the sleeve S making contact therewith. The sleeve S extends 80 down into the body of the plug and is knurled outwardly at its lower end at T to hold the insulating material firmly thereon. The sleeve S being hollow extends over and beyond the tip B' of the core wire B and 85 preferably at a slight distance therefrom. The electricity flowing from the line terminal K to the sleeve S is caused to jump in the atmosphere to the line wire B, this produces an intensive effect upon well known 90 principles. The screwing of the cap containing the insulating material forces the ground J outwardly and insulates it exactly the same as shown in Fig. 5.

In order to operate the device the plug 95 is assembled as shown in Fig. 2, or with the alternative construction as shown in Fig. 5. It is screwed into the cylinder head in the ordinary manner and the line wire is attached thereto and it operates in the usual 100 manner therefrom. When it is desired to reverse it the terminal M or K, as the case may be, is changed to the opposite end of the plug and assembled in the manner shown. Thereupon the proper adjustment 105 is made between the ground line terminal J and the core wire B, it being readily understood by those skilled in the art that such adjustment must be made within narrow limits, say about one-fiftieth of an inch. 110 The plug is thereupon screwed into the cylinder head in the usual manner with the

22 *Double ended spark plug*

opposite end inside of the cylinder. The line wire is attached and the plug operated the same as any single plug would operate in the manner well understood by those skilled in the art.

Having thus described my invention what I claim is:

1. In a double ended spark plug, a sparking ground terminal at each end thereof, a core line provided with a sparking terminal at each end, means for connecting a line wire to either end of said core line, and means for insulating said core line at the end connected to the line wire from its corresponding ground terminal.
2. In a double ended spark plug, a double ended insulating core traversed by a core line, a sparking ground terminal disposed at each end of said spark plug to coact with the corresponding end of the core line, means for attaching a line wire at each end of said core line, an insulating sleeve adapted to be superimposed over the end of the core line between the core line and its corresponding ground terminal and adapted to be held in place by the means attaching the line wire to the core line.
3. In a double ended spark plug, a sparking ground terminal combined with a casing at each end thereof, a double ended insulating core traversed by a core line carried by said casing, a screw cap carrying an insulating sleeve adapted to be screwed over either end of said spark plug, said insulating sleeve adapted for insertion between 35 said core line and its corresponding sparking ground terminal, a metallic conductive lining in said insulating sleeve, means for connecting a line wire with said lining.
4. In a double ended spark plug, a double ended insulating core traversed by a core line and screw threaded at each end, a sparking ground terminal carried at either end of the casing of said spark plug and projecting into the opening thereof so as to be 45 in sparking proximity with said core line, a screw cap adapted to screw over either end of said spark plug, an insulating sleeve carried by said screw cap and adapted to be fitted over the end of said core line between 50 the sparking ground terminal and said core line, and means for connecting said core line to the line wire.
5. In a double ended spark plug, a double ended insulating core traversed by a core line, a sparking ground terminal at each end of said spark plug carried by the casing and projecting into the interior longitudinal opening of said casing and partially circumferentially surrounding said core line, 55 means for attaching a line wire at either end of said core line, means for insulating said core line from its corresponding sparking ground terminal.

In testimony whereof, I sign this specification.

ANDREW L. KULICK.
